UNITED STATES PATENT OFFICE.

CHARLES F. HENNING, OF CHICAGO, ILLINOIS.

GARMENT-COLLAR.

SPECIFICATION forming part of Letters Patent No. 397,289, dated February 5, 1889.

Application filed August 4, 1888. Serial No. 281,932. (No model.)

To all whom it may concern:

Be it known that I, CHARLES F. HENNING, of Chicago, in the county of Cook and State of Illinois, have invented certain new and useful Improvements in Garment - Collars; and I do hereby declare that the following is a full, clear, and exact description thereof, reference being had to the accompanying drawings, and to the letters of reference marked ⁵ thereon, which form a part of this specification.

This invention relates to an improvement in collars for ladies' cloaks, fur capes, coats, and other similar garments.

¹⁵ The object of the invention is to provide means for holding the front points or ends of the collar, where the same open at the neck, at several different angles or positions—as, for instance, either closed against the neck, ²⁰ half-way open, or turned back against the body of the garment.

A device embodying my invention embraces as its main or principal feature two flat metal plates attached to the body of the garment ²⁵ and to the folding part of the collar, said plates being connected by a hinged joint embracing a spring attached to one plate and arranged to bear upon one or more flat faces of a part attached to the other plate, so that the ³⁰ plate attached to the collar may be held at any desired angle, determined by the position of the said flat face or faces, while at the same time the collar may be easily turned or moved by simple pressure on the plate connected therewith. The plates referred to will commonly be placed between the layers of material composing the garment.

The invention consists in the matters hereinafter described, and pointed out in the ⁴⁰ appended claim.

In the accompanying drawings, illustrating my invention, Figure 1 is a perspective view of the upper part of a garment, showing the standing collar in its intermediate position, ⁴⁵ the collar being shown in dotted lines as closed against the neck. Fig. 2 is a plan or face view of one end of the collar and the adjacent part of the body of the garment, the outer layer of the garment being broken away ⁵⁰ to show the hinged plates. Fig. 3 is an enlarged detail section of the hinged plates.

Fig. 4 is a similar section showing a modified form of the same.

As shown in the said drawings, A is the body of the garment, B the collar, and ⁵⁵ b b the end parts or points of the collar, the position of which is controlled by the device constituting my invention.

C is a metal plate attached to the body of the garment adjacent to the end portion, ⁶⁰ b, of the collar.

D is another plate attached to the said part b of the collar.

The plates C and D are flat or approximately so, and may be secured to or between ⁶⁵ the layers of cloth or other material comprising the garment in any desired manner—as, for instance, the plates may be provided with holes c c d d and sewed to the garment in the manner illustrated. The said plates C and ⁷⁰ D are hinged together or pivotally connected with each other by means of a pivot-pin, E, passing through eyes or knuckles on the plates in the manner of an ordinary hinge. The pivotal axis of the plates is arranged to ⁷⁵ coincide as near as possible with the line of fold of the collar, so that in turning the ends of the collar or folding the entire collar the plate will flex or bend with the collar, and their presence will not be noticeable to the ⁸⁰ eye.

The pivot-pin E is rigidly connected with one of the plates—in this instance the plate D, which is attached to the collar—and the other plate, C, is provided with a spring or ⁸⁵ spring-arm, F, which bears against a part of said pivot-pin which is exposed at the central part of the hinge. Such exposed part of the pin (indicated by E' in the drawings) is made larger than other parts of the pin, and is provided with flat faces e' e'', adapted to be engaged by the spring F as the plate D is turned or moved. When the spring is pressing against one of said flat faces, some little pressure is required to turn or move the plate, and it follows that the said spring, in combination with the pin provided with flat faces, in the manner described, serves as a means of holding the plates C and D at a desired angle with each other and the ends b of the collar in a ⁹⁵ desired position when the plate C is held immovable by its attachment to the body of the ¹⁰⁰ garment.

garment when the latter is on the person of the wearer.

The part E' of the pin E is shown in the drawings, Fig. 3, as provided with three flat faces adapted to hold the ends of the collar closed or standing against the neck in a position inclined or flaring outwardly and in an intermediate position. A greater or less number of such flat faces may, however, be used to afford a desired number of positions in the collar—as, for instance, I have shown in Fig. 4 a plate having two flat surfaces adapted to hold the collar either closed or standing partially open.

15 The spring F is shown as having the form of a flat leaf-spring riveted to the plate C. The particular construction in the joint illustrated, although a simple and desirable one, is not essential, and any one of a number 20 of well-known forms of joint, embracing a part attached to and moving with one plate and having flat surfaces or made of cam shape

and a spring or spring-actuated part acting upon the flat or cam surfaces of said part to hold the same in a desired position or positions, may be employed in place of the particular joint herein shown. 25

I claim as my invention—

The combination, with the main part or body of a garment and the collar thereof, of 30 hinged plates attached to the body and the collar, one of said plates being provided with a flat surface or surfaces adjacent to its pivotal axis, and the other with a spring-actuated part bearing upon said flat surface, substantially as described. 35

In testimony that I claim the foregoing as my invention I affix my signature in presence of two witnesses.

CHARLES F. HENNING.

Witnesses:
